ATTORNEY

Patented Sept. 12, 1922.

UNITED STATES PATENT OFFICE.

WILLIAM H. WARD, OF ASHTABULA, OHIO.

WRENCH.

Application filed June 4, 1919. Serial No. 301,627.

To all whom it may concern:

Be it known that WILLIAM H. WARD, a citizen of the United States of America, residing at Ashtabula, in the county of Ashtabula and State of Ohio, has invented new and useful Improvements in Wrenches, of which the following is a specification.

The object of the invention is to provide a new and novel form of wrench adapted for use with pipes and various forms of nuts, the wrench being of a character that will permit its firmly gripping the pipe or nut with which it is engaged, the grip increasing as the force on the wrench is increased. 15 The construction permits the ready release of the wrench from the nut or pipe with which it is engaged.

The invention is illustrated and described in a specific embodiment, to which, however, 20 it is not to be restricted. The right is reserved to make such changes or alterations as the actual reduction to practice may suggest, in so far as such changes or alterations are compatible in spirit with the annexed claim.

25 In the accompanying drawings:

Figure 1 is a side elevational view of the improved wrench.

Figure 2 is an edge elevational view.

Figure 3 is a section on the line 3—3 of 30 Figure 2.

As shown, the invention comprises the two plates 1, of the shape shown, these two plates being secured together with a jaw element between them, this jaw element comprising the smooth edge jaw 2 and its attendant shank 3, the latter being positioned between the two plates and the whole being secured together with appropriate fasteners 4, which pass through the plates and through 35 the shank 3. These fasteners are preferably rivets although it is obvious that screws or bolts may be effectively employed for this purpose. The jaw 2 projects beyond the plates 1 and the shank 3 lies adjacent the 40 side edges of the plates and conforms to the shape of the plates at these side edges, the inner edge of the shank being formed with an arcuate or curved depression 5 adjacent its lower end.

45 Mounted opposite the jaw 2 there is a toothed jaw 6, this latter being formed with a shank 7 similar in shape to the shank 3 and having a curved or arcuate depression 8 opposite the depression 5. This jaw 6, however, is mounted for pivotal movement with

reference to the plates and to that end a pivot member 9 is provided in the form of a rivet or screw stud, the pivot member 9 being passed through and secured in the two plates 1 opposite the upper of the fasteners 4. The shank 7 is formed with an eye through which this pivot member 9 loosely passes and it is apparent that the jaw 6 may swing on this pivot member 9. Carried between the two plates and supported on a pivot stud or rivet 10 secured in the two ends of a handle 11, this handle being formed at its upper end with a disk like head 12 which lies between the lower ends of the shanks of the two jaws and in the depressions 5 and 8. The swinging of the handle 11 on its pivot stud 10 will obviously operate to swing the jaw 6 towards the jaw 2 and will serve to tighten the grip of the jaws on the nut or pipes to which the wrench is attached, and 75 whether the wrench be used for screwing up or unscrewing a nut or pipe, it can, if properly attached to the said nut or pipe be made to tighten its grip on the same as the force effecting the screwing up or unscrewing operation is increased. Obviously the movement of the handle in the opposite direction from that above mentioned will release pressure on the jaw 6 and thereby provide for the effective and ready release of 85 the wrench from the nut or bolt when desired.

It is to be observed that the jaws, being formed with circular recesses in their shanks embracing the disk like head 12 of the handle 90 will permit a comparatively wide angular movement of the handle before any camming action of the handle will ensue to operate the movable jaw. The necessity for having a spring in connection with the movable jaw 95 is therefore avoided and the finger or thumb may be placed on the shank of the movable jaw and the shank kept in contact with the disk like head until the jaws of the wrench are engaged with the work. Then the handle 100 may be grasped and the unscrewing or screwing up operation proceeded with. By this construction, unless the jaws are engaged with the work, the handle only functions to tighten the jaws on the work and there is no appreciable movement of the movable jaw. Furthermore by providing the disk like head 12, it is not necessary to have the handle in direct alignment with the device in order that the jaws may be 110

opened their full width, such as would be the case were the wrench constructed on the principle of compound leverage.

The invention having been described, what is claimed as new and useful is:

A wrench comprising a pair of plates, a jaw having a shank mounted between said plates and rigidly secured thereto, a second jaw having a shank pivotally supported be-

tween said plates, and a handle formed with a disk like head and pivotally supported between the plates with the pivot concentric with the head, the two jaws being formed with recesses in their shanks concentric to the head and embracing the latter on opposite sides of its center.

In testimony whereof I affix my signature.

WILLIAM H. WARD.
